UNITED STATES PATENT OFFICE.

WASHINGTON BRYANT, OF BATESVILLE, ARKANSAS.

IMPROVEMENT IN DEVICES FOR PARING HORSES' HOOFs.

Specification forming part of Letters Patent No. 147,896, dated February 24, 1874; application filed January 17, 1874.

To all whom it may concern:

Be it known that I, WASHINGTON BRYANT, of Batesville, in the county of Independence and State of Arkansas, have invented a new and valuable Improvement in Tools for Trimming Horses' Hoofs; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a top view of my hoof-trimmer. Fig. 2 is a bottom view of the same. Fig. 3 is a sectional, and Fig. 4 a detail, view of the same.

This invention has relation to devices for trimming horses' hoofs preparatory to applying the shoes; and it consists in a rotary trimmer, a flanged holder therefor, and a hoof-holding ring, combined as will be hereinafter explained; also, in making the hoof-holding ring removable from its flange, so that rings corresponding in their diameter to different-sized hoofs can be used, as will be hereinafter shown.

The following is a description of my invention:

In the annexed drawings, A represents a circular head, through which several trimming-knives, *a*, are passed, which are made adjustable, like the knives of a hand-plane, for taking off different thicknesses of shavings. Four knives are shown in the drawings, but a greater or less number may be used. This cutter-head, which presents a flat bottom surface, is centrally secured on a short shaft, B, which is adapted to fit into the socket of a common breast-brace, for rotating it, and which has its bearing in a tube, C. This tube C has four

curved arms radiating from its lower end, which have secured to them a circular flange, *b*, of greater width than the thickness of the head A. The flange or hoop *b* surrounds the trimming-head A, and allows the latter to rotate freely in it. G designates a ring of suitable thickness and diameter, which ring is secured to the inner side of the flange *b*, beneath the head A, by means of pins *c c* and a spring-catch, *c'*.

To use this instrument, the bottom or cutting face of the head A is placed upon the hoof, the latter being properly held up by the shoer, and a curved shield, D, is adjusted against the wrist of the left hand, in which the hoof is held; then, by means of a common brace affixed to the shaft B, the shoer turns the cutter-head, and trims perfectly even the hoof.

The ring G, in which the hoof is held and centered, is removable for the purpose of substituting in its stead rings of different diameters interiorly.

What I claim as new, and desire to secure by Letters Patent, is—

1. The cutter-head A on a shaft which has its bearings in a tube, C, whose arms carry a flange, *b*, surrounding the cutter-head, constructed and adapted for trimming the hoofs of animals, substantially as described.

2. The removable ring G, attached to flange *b*, and combined with the cutter-head A, substantially as and for the purposes described.

In testimony that I claim the above I have hereunto subscribed my name in the presence of two witnesses.

WASHINGTON BRYANT.
